(57) **CLAIM**

The ornamental design for a timer controller, as shown and described.

DESCRIPTION

FIG. 1 is a perspective view of the timer controller.

FIG. 2 is a top plan view of the timer controller.

FIG. 3 is a bottom view of the timer controller.

FIG. 4 is a front elevational view of the timer controller.

FIG. 5 is a rear elevational view of the timer controller.

FIG. 6 is a right side view of the timer controller; and,

FIG. 7 is a left side view of the timer controller.

The broken line showing of parts of the timer controller is for illustrative purposes only and forms no part of the claimed design.
